CLASP

Charles A. Nash, Seattle, Wash.

Application January 17, 1942, Serial No. 427,170

3 Claims. (Cl. 24—245)

This invention relates to a new and improved type of clasp or garter button, and has for one of its objects the production of a simple and efficient means for facilitating the secure attachment of a garter button to a stocking, and the like.

A further object of this invention is the production of a simple and efficient means for securing the two sections of a garter button together, and also for firmly holding the button in engagement with a stocking or the like, without danger of injuring the fabric of the stocking.

Other objects and advantages of this invention will appear throughout the following specification and claims.

In the drawing—

Figure 1 is a front elevational view of the button in a stocking-engaging position;

Figure 2 is a vertical sectional view taken on line 2—2 of Figure 1;

Figure 3 is a rear elevational view;

Figure 4 is a horizontal sectional view taken on line 4—4 of Figure 1;

Figure 5 is a perspective view of the button with the sections drawn apart or in a separated position;

Figure 6 is a front elevational view of the primary section of the button;

Figure 7 is a side elevational view of the primary section of the button;

Figure 8 is a vertical sectional view taken on line 8—8 of Figure 7;

Figure 9 is a front elevational view of the co-acting section of the button;

Figure 10 is a vertical sectional view taken on line 10—10 of Figure 9.

By referring to the drawing, it will be seen that 10 designates the primary section of the button and 11 indicates the co-acting or clamping section of the button. The primary section 10 comprises a circular disc having an elongated slot 12 near the top and extending transversely thereof for receiving a suspending elastic garter A. An annular protruding flange 13 is carried by the front face of the section 10 below the slot 11. An outwardly extending neck 14 projects from the flange 13 and this neck 14 supports at its outer end an elliptical knob 15, the elongated axis of which knob extends in line with the vertical axis of the primary section 10, as shown. The upper and lower ends 16 and 17, of the knob 15 project beyond the sides of the neck 14 to provide projecting lips, as shown in detail in Figures 6 and 8.

The co-acting section 11 comprises a flat disc 55

having a projecting tongue 18 at the top end thereof and a transversely extending elongated slot 19 is formed in the tongue 18 for receiving a suspending elastic garter portion B. The section 11 is provided with a centrally located elliptical aperture 20 and the outer face of the section 11 is raised along its outer edge to provide an annular rim 22 which surrounds the inset central portion 23. The elongated axis of the elliptical aperture 20 extends in a horizontal plane or normally at right angles to the elongated axis of the knob 15. The inner or under face of the co-acting or clamping section 11 is dished to provide a cushion pocket 24 into which the fabric of the stocking may be fitted when the sections of the button are assembled.

The present type of clasp illustrated may be made of plastic material and may possess spring characteristics which will allow the parts to yield under undue stress to provide the proper cushioning effect.

The device may be used in connection with sanitary belts for holding sanitary pads to the belt and may be used with other belts and for supporting other articles.

When assembling the button, the section 11 is turned to a position where the elliptical aperture extends in line with the knob 15 and the fabric of the stocking is placed over the knob 15. The knob 15 and fabric are then extended through the aperture 20 and the section 11 then returns to its normal position where the elliptical aperture 20 extends at right angles to the knob 15, with the ends 16 and 17 overlapping the edges of the aperture 20 to retain the knob 15 in engagement with the section 11. The fabric of the stocking fitting between the sections 10 and 11, within the cushion pocket 24, will tend to provide a cushion to normally urge the sections apart and normally hold the section 11 tightly in contact with the overhanging ends 16 and 17 of the knob 15. This action will efficiently hold the sections of the button in a clamped or locked position until the section 11 is turned to release the knob 15 from engagement with the aperture 20, at which time the sections 10 and 11 may be separated and the fabric of the stocking released from the button.

It should be noted that the flange 13 of the primary section 10 acting in conjunction with the cushion pocket 24 in the section 11 are very important features since they provide an efficient securing and holding means which will not tend to tear the finest of fabrics. In other words, the flange 13 will tend to force the fabric up into the

concave pocket 24 thereby preventing the fabric from becoming pinched between two pinching surfaces which might result in tearing or injuring the fabric.

It should be understood that certain detail changes in the construction may be employed without departing from the spirit of the invention, so long as such changes fall within the scope of the appended claims.

Having described the invention, what I claim is:

1. A clasp of the class described comprising a primary section having a projecting neck, an elliptical knob carried by the outer end of said neck, the knob having projecting lips extending beyond the upper and lower faces of the neck, the elongated axis of the elliptical knob normally extending in a vertical plane, a co-acting section adapted to fit over the primary section, said co-acting section having an elliptical opening, the elongated axis of which extends normally at right angles to the elongated axis of the knob, the co-acting section being adapted to be rotated to cause the knob to extend through said opening and the co-acting section being rotatable to extend said opening at right angles to the knob in a manner whereby the lips of said knob will overhang the side edges of said opening and firmly hold the co-acting section in clamping relation, said co-acting section being concave on its inner face adjacent said opening to provide a cushioning pocket.

2. A clasp of the class described comprising a primary section having a projecting neck, an elliptical knob carried by the outer end of said neck, the knob having projecting lips extending beyond the upper and lower faces of the neck, the elongated axis of the elliptical knob normally extending in a vertical plane, a co-acting section adapted to fit over the primary section, said co-acting section having an elliptical opening, the elongated axis of which extends normally at right angles to the elongated axis of the knob, the

co-acting section being adapted to be rotated to cause the knob to extend through said opening and the co-acting section being rotatable to extend said opening at right angles to the knob in a manner whereby the lips of said knob will overhang the side edges of said opening and firmly hold the co-acting sections in clamping relation, said co-acting section being concave on its inner face adjacent said opening to provide a cushioning pocket, and said primary section having an annular flange formed around the base of said neck and adapted to force fabric gripped between the sections into said cushioning pocket.

3. A clasp of the class described comprising a primary section having a projecting neck, an elliptical knob carried by the outer end of said neck, the knob having projecting lips extending beyond the upper and lower faces of the neck, the elongated axis of the elliptical knob normally extending in a vertical plane, a co-acting section adapted to fit over the primary section, said co-acting section having an elliptical opening, the elongated axis of which extends normally at right angles to the elongated axis of the knob, the co-acting section being adapted to be rotated to cause the knob to extend through said opening and the co-acting section being rotatable to extend said opening at right angles to the knob in a manner whereby the lips of said knob will overhang the side edges of said opening and firmly hold the co-acting sections in clamping relation, said co-acting section being concave on its inner face adjacent said opening to provide a cushioning pocket, said primary section having an annular flange formed around the base of said neck and adapted to force fabric gripped between the sections into said cushioning pocket, said co-acting section having a projecting tongue at the top thereof, the tongue having an elongated slot, a suspending means passing through said slot, and said suspending means also engaging said primary section.

CHARLES A. NASH.
